UNITED STATES PATENT OFFICE.

FREDERICK W. LINDEMANN, OF ST. PAUL, MINNESOTA.

GARMENT PRESS.

Application filed January 15, 1925. Serial No. 2,633.

To all whom it may concern:

Be it known that I, FREDERICK W. LINDEMANN, a citizen of the United States, residing at St. Paul, in the county of Ramsey and State of Minnesota, have invented certain new and useful Improvements in Garment Presses; and I do declare the following to be a full, clear, and exact description of the invention, such as will enable others skilled in the art to which it appertains to make and use the same.

My invention relates to useful improvements in garment presses and the present disclosure has reference more particularly to presses of the type in which a pressing head is carried by a vertically movable lever and is movable toward and from a stationary pressing member commonly known as a buck.

One object of the invention is to provide unique means for locking the pressing head in operative position, said means including a fly-wheel which is set in motion by initial movement by the operator of said pressing head and thereafter expends its kinetic energy to assist in completing the movement of said pressing head.

A further object is to so relate the fly-wheel with associated parts, as to cause it to substantially counterbalance the weight of the pressing head permitting the latter to be easily manipulated.

A still further aim is to provide a press which will be rather simple and inexpensive, yet will be efficient, durable and in every way desirable.

With the foregoing in view, the invention resides in the novel subject matter herein-after described and claimed, the description being supplemented by the accompanying drawings.

Figure 1 is a side elevation of the press showing the parts in operative position.

Figure 2 is a fragmentary side elevation illustrating the manner in which the locking means for the pressing head is tripped to permit raising of said head.

Figure 3 is a diagram illustrating the press in substantially an open position.

Figure 4 is a rear elevation of the upper portion of the press.

Figure 5 is a top plan view.

Figure 6 is a detail sectional view as indicated by line 6—6 of Fig. 1.

In the drawings above briefly described, the numeral 1 designates the conventional

form of frame structure, upon which the buck 2 is mounted in the well known manner, said frame structure being provided, in the present disclosure, with a pair of standards 3 disposed behind said buck. Extending between the upper ends of these standards, a horizontal shaft 4 has been shown, which shaft supports a pair of substantially horizontal, vertically swinging levers 5. The shaft 4 constitutes a fulcrum for the levers 5 and is located between the ends of the latter. The front ends of these levers carry the usual pressing head 6 which is provided with an appropriate handle 7, by means of which it may be moved toward and from the buck 2. In the construction shown, the rear ends of the levers 5 are connected by a horizontal rod or shaft 8, upon which two spaced fly-wheels 9 are mounted, said fly-wheels being sufficiently heavy to substantially counterbalance the weight of the pressing head 6, so that the latter may be easily raised and lowered. By means of an appropriate wrist pin connection 10, the fly-wheels 9 are connected with the upper end of a link 11 whose lower end is pivotally supported by a transverse rod or the like 12 which is carried by the frame structure 1. This link is preferably adjustable, and it may well be constructed as detailed in Fig. 6. An arched yoke 13 has been shown mounted pivotally on the rod 12, and swiveled in this yoke, is a screw 14 having threaded connection with a bearing 15 which constitutes part of the wrist pin connection 10, said screw 14 being provided with a hand wheel or other appropriate means 16, so that it may be rotated as required. When this wheel is turned in a direction to lengthen the link 11, pressure will be increased on the garment being pressed, while rotation of the wheel in the other direction will decrease the pressure, as will be readily understood.

The shafts 8 and 12 and the wrist pin connection 10 are so related that when the press is completely closed as shown in Fig. 1, said connection 10 will be either on dead center or a slight distance beyond the same, so that the press is effectively locked in closed position, until the link 11 and wheels 9 are moved to shift the connection 10 off dead center, whereupon the press may be opened. Means are provided for moving the link and fly-wheels in the manner just referred to, and such means acts to set the fly-wheels in motion, the kinetic energy thus

developed being expended by the fly-wheels to assist in quickly and easily moving the press to an open position. When in this position, the parts stand in a relation which 5 will be clear from Fig. 3, and when the handle 7 is pulled downwardly to close the press, movement of the levers 5 will set the fly-wheels 9 in motion, so that they may also expend kinetic energy to assist in quickly 10 and easily closing the press.

Just as soon as closed position is reached, the wrist pin connection 10 either arrives on dead center or at a point slightly beyond such center, so that the press is tightly 15 locked in closed position until released by the operator. For effecting such release, I prefer to provide the construction described below.

A stop 17 has been shown projecting laterally from one of the fly-wheels 9, said stop 20 engaging the lower side of a relatively stationary stop 18 when the press is closed as seen in Fig. 1. The stop 18 may well be formed by laterally directing the upper end 25 of a substantially vertical rod 19 which is slidable through an appropriate guide 20 carried by the frame structure 1, said rod being provided with a stop collar 21 which abuts the guide 20, so as to limit the upward 30 movement of the rod and consequently insure that the co-acting stops 17 and 18 shall limit the rotation of the fly-wheels 9, when the press is closed. The lower end of the rod 19 is preferably connected to a pedal 35 22 which is normally raised by an appropriate spring 23.

When the press is closed, as in Fig. 1, a downward push on the pedal 22, shifts the wrist pin connection 10 off dead center as 40 will be clear from Fig. 2, so that the press may be easily opened, and as the opening movement is started, the fly-wheels 9 are set in motion, so that they assist in completing the opening movement, as above set 45 forth. As soon as the operator removes his foot from the pedal 22, the spring 23 restores said pedal and the rod 19 to their initial positions, so that the stop 18 will be in readiness to limit the rotation of the fly-wheels 9 when the press is again closed, by 50 pulling the handle 7 downwardly. During this closing movement, it will be remembered, that the motion of the fly-wheels is instrumental, as above explained.

It will be seen from the foregoing that a 55 very advantageous press has been provided, and while excellent results are obtainable from the construction disclosed, it is to be understood that such disclosure is for illustrative purposes only, and that within the scope of the invention as claimed, numerous 60 modifications may be made. For instance, while two levers 5, two fly-wheels 9 and connections between them have been shown, 65 it will be obvious that in some instances,

only one lever and one fly-wheel could well be used. Moreover, while the particular form of adjustable link 11 which I have disclosed, as well as the unique stopping and tripping means for the fly-wheels, may be 70 preferred, it will be understood that these parts could well assume other forms.

I claim:

1. A garment press comprising a pressing head mounted for movement to and from 75 pressing position, and means for locking said head in pressing position, said means including a fly-wheel and means connected therewith whereby the same is set in motion by initial movement of the head, said fly-wheel thereafter expending its kinetic energy to assist in completing the movement of said head.

2. A press as specified in claim 1; said fly-wheel being associated with said head 80 in a manner to substantially counterbalance the same.

3. A garment press comprising a lever fulcrumed between its ends and having a pressing head at one end, and means for locking 90 said lever in pressing position, said means including a fly-wheel mounted on the other end of the lever and means connected with said fly-wheel whereby the same is set in motion by initial starting of said lever, said fly-wheel thereafter expending its kinetic energy to complete the movement of the lever.

4. A garment press comprising a supporting structure, a vertically movable lever fulcrumed between its ends thereon and having a pressing head at one end, a fly-wheel mounted on the other end of said lever and substantially counterbalancing the weight of 100 said pressing head, a link pivoted at its lower end to the aforesaid supporting structure, and having a wrist pin connection with said fly-wheel, said connection being adapted to move to or beyond dead center when the above named lever is in pressing position, whereby to lock the presser head lowered, and operator controlled means for moving 105 said wheel and link to released position to permit raising of said head.

5. A garment press comprising a supporting structure, a vertically movable lever fulcrumed between its ends thereon and having a pressing head at one end, a fly-wheel mounted on the other end of said lever and substantially counterbalancing the weight of 110 said pressing head, a link pivoted at its lower end to the aforesaid supporting structure and having a wrist pin connection with said fly-wheel, said connection being adapted to move to or beyond dead center when the above named lever is in pressing position, whereby to lock the presser head lowered, and operator controlled means for limiting 115 the movement of said fly-wheel and link when said lever is moved to operative position.

tion and for moving said wheel and link to released position to permit raising of said head.

6. A garment press comprising a supporting structure, a vertically movable lever fulcrumed between its ends thereon and having a pressing head at one end, a fly-wheel mounted on the other end of said lever and substantially counterbalancing the weight 10 of said pressing head, a link pivoted at its lower end to the aforesaid supporting structure and having a wrist pin connection with said fly-wheel, said connection being adapted to move to or beyond dead center, when the 15 above named lever is in pressing position, whereby to lock the presser head lowered, a stop carried by the aforesaid fly-wheel and having a portion facing upwardly when the parts are in pressing position, a substantially 20 vertical rod slidably mounted on the supporting structure and having a lateral projection at its upper end overlying said stop when the press is in operation, means for limiting the upward movement of said rod, 25 and a spring-raised pedal connected with said rod for depressing it to move the aforesaid wheel and link off dead center.
7. A garment press comprising a supporting structure, a vertically movable lever fulcrumed between its ends thereon and having a pressing head at one end, a fly-wheel 25

mounted on the other end of said lever and substantially counterbalancing the weight of 30 said pressing head, a link pivoted at its lower end to the aforesaid supporting structure and having a wrist pin connection with said fly-wheel, said connection being adapted to move to or beyond dead center, when the 35 above named lever is in pressing position, whereby to lock the presser head lowered, a stop carried by the aforesaid fly-wheel and having a portion facing upwardly when the parts are in pressing position, a substantially 40 vertical rod slidably mounted on the supporting structure and having a lateral projection at its upper end overlying said stop when the press is in operation, means for limiting the upward movement of said rod, 45 and a spring-raised pedal connected with said rod for depressing it to move the aforesaid wheel and link off dead center.

8. A garment press comprising a pressing head, a lever on which it is mounted, a fly 50 wheel mounted on said lever, and means connecting an off-center part of said fly wheel with a stationary part of the press.

In testimony whereof I have hereunto affixed my signature.

FREDERICK W. LINDEMANN.
